UNITED STATES PATENT OFFICE.

MICHAEL COSTELLO, OF JERSEY CITY, NEW JERSEY.

COMPOUND CONDIMENT HOLDER.

Application filed December 15, 1926. Serial No. 154,870.

This invention relates to condiment holders and has for its object the provision of a compound holder embodying in a single structure two shakers or distributors adapted to contain salt and pepper or other condiments which may be brought into use selectively.

It is a further object of this invention to provide a compound holder embodying two shakers in which ready flow of the condiments is assured.

Finally it is an object of this invention to provide a compound holder which is simple to construct, convenient to use and efficient in its operation.

These and other objects of the invention will be apparent from the following description taken in connection with the accompanying drawing in which:

20 Figure 1 is a front elevation of the holder; Figure 2 is a side elevation of the holder;

Figure 3 is a sectional view taken along the lines 3—3 of Figure 2;

25 Figure 4 is a plan view of the holder;

Figure 5 is a fragmentary view in elevation showing the closure for the holder in one of its operative positions and,

Figure 6 is a perspective of the holder showing the manner of using the same.

30 Referring to the drawing the holder is formed of a base member 11 of any suitable material such as glass, celluloid, wood or metal and is provided with the cylindrical cavities 12, having the square opening 13 at the bottom. In the cavities 12 are fitted the containers 14 for the condiments. These

35 containers may be made of any suitable material such as glass, metal, paper or celluloid. The containers are readily removable and replaceable and as a sales feature of this device it is possible for the seller of condiments to bring the condiment on the market in containers properly designed to be inserted in the cavity 12 for ready use with the container. The cavities 13 in the bottom of the base are preferably square.

40 Fitted over the base member 11 is the cap 15 which is provided with the side arms 16 having nipples 17 which fit into the depressions 18 in the sides of the base 11 for the purpose of holding the cap 15 in place. There is thus provided a covering which is simple in its construction and which is very easily removable. The cap 15 is provided

45 with ears 19 in which the pin 20 is jour-

nalled. The bar 21 is pivoted upon the pin 20 and is provided for tilting motion downwardly and upwardly. The spring 22 is also carried by the cap 15 and is provided to hold the bar 21 normally in the horizontal position as indicated in Figures 1 and 3. The top of the cap 15 is provided with perforations 23 which permit the flow of the material from the containers or reservoirs 14. The bar 21 is provided with projecting pins 24 which are so shaped and arranged as to register with the perforations 23 when the bar 21 is in the normal position as shown in Figure 3. These pins, therefore, serve as a closer for the perforations and when it is desired to permit the flow of material from either one of the containers 14 it is merely necessary to depress one side of the bar 21 thereby freeing the projections 24 from the perforations 23 and at the same time maintaining the other pins and perforations in registry. This is clearly shown in Figure 5.

50 In order to enable the holder to be conveniently handled and manipulated the handles 26 shown in Figures 2 and 4 of the drawing are provided. Thus the user may grip the handle 26 by means of one or two fingers and use the thumb of the same hand to depress either side of the bar 21 to obtain the desired flow of the condiment.

55 While I have disclosed and described a specific embodiment of my invention I do not intend to be limited to the specific details described, but I desire to secure protection upon all aspects of the invention as 60 defined in the appended claims.

Having thus described my invention, what I claim is:

1. In a condiment holder having separate reservoirs a flat cover member closing said reservoirs, said cover member being provided with a first group of perforations for one reservoir and a second group of perforations for a second reservoir, a flat bar provided with projection arranged to register with all of said perforations normally to close the same, and means whereby the bar may be tilted to withdraw the projections from one group of perforations while maintaining certain projections in said other group of 65 perforations.

2. A condiment holder having two separate reservoirs provided with a flat top, a cover for said reservoirs, said cover being provided with perforations, a flat unitary 70

means normally to close all perforations in said cover, said means being pivotally mounted on said holder, a first handle whereby the holder may be held by the fingers of the user and the said means pivoted by the thumb of the user to free the perforations of one cover while said other perfora-

tions are held closed, and a second handle whereby the holder may be held by the fingers of the user and the said means pivoted by the thumb of the user to open said closed perforations and to close said open perforations. 10

MICHAEL COSTELLO.
